UNITED STATES PATENT OFFICE

HENRY C. JURS, OF ALLIANCE, OHIO

FURNACE

Application filed December 22, 1930. Serial No. 503,900.

The present invention relates broadly to furnace structures, and more particularly to muffle furnaces of the type especially adapted for enameling processes.

In the art of enameling, it is essential that the combustion gases be maintained out of contact with the articles being enameled, for the reason that contact of such gases with the enamel coating objectionably discolors the same. The difficulties of satisfactorily operating combustion furnaces has led to attempts to substitute electrically heated furnaces in which the problem of discoloring gases does not exist. While such furnaces have satisfactorily performed their intended duty, they have been open to the objection of extremely high cost of operation.

It is one of the objects of the present invention to provide a furnace of improved construction effective for maintaining the combustion gases out of contact with the enameled articles. It is also one of the objects of the invention to provide a furnace of such improved construction that more efficient heating and therefore a lower fuel consumption is obtained.

In the accompanying drawings I have shown for purposes of illustration only, a preferred embodiment of the invention. In the drawings:

Figure 1 is a horizontal longitudinal sectional view through a furnace constructed in accordance with the present invention;

Figure 2 is a transverse sectional view on the line II—II of Figure 1, looking in the direction of the arrows; and

Figure 3 is a vertical longitudinal sectional view on the line III—III of Figure 2, looking in the direction of the arrows.

In accordance with the present invention there is provided a suitable base 2 of concrete or similar material from which side walls 3 and 4, and end walls 5 and 6 extend upwardly to the desired height. The side walls 4 and the end walls 6 are preferably solidly built up of fire brick, and being enclosed by the air sealed insulating side walls 3 and end walls 5, constitute an outer furnace shell free from sprung arches, as hereinafter pointed

out, and form a rigid insulated chamber within which the muffle proper is constructed.

Formed in the fire brick bottom 2 is a combustion chamber 9 within which is mounted a series of piers 10 of suitable size, height and number for supporting a refractory floor 11. This floor is herein illustrated as comprising a series of individual sections having interfitting joints 12 to insure a substantially tight floor such as to prevent the flow of combustion gases from the combustion chamber 9 into the firing chamber 8.

Extending through the walls at suitable points are burner openings 14 adapted to supply the gas or oil for combustion purposes. The fuel burning within the combustion chamber 9 travels upwardly from the combustion chamber through muffles 15 located preferably throughout the entire length of the firing chamber adjacent each side thereof. These muffles, as clearly illustrated in Figure 3 of the drawings, are open at their bottom ends to the interior of the combustion chamber so as to freely receive combustion gases therefrom. Each of the muffles is herein illustrated as comprising a plurality of suitably superimposed sections, all of the sections being located physically within the firing chamber and spaced from the walls thereof so as to provide a free radiating surface entirely therearound. At their upper ends they underlie and support a suitable refractory structure 16, preferably of fire-brick, having formed therein a horizontal flue 17 which, as illustrated in Figure 3 of the drawings, communicates at one end with a stack opening 18.

The refractory structure 16 being carried directly by the upper ends of the muffles 15, is free to move up or down thereon and thereby follow dimensional changes in the length of the muffles caused by heating and cooling thereof, while always retaining an operative relationship therewith. The bottom wall of the refractory structure 16 is formed with a series of openings 19, each of which is in substantial alignment with one of the muffles so as to permit the same to freely discharge into the horizontal flue 17.

At one side, the refractory structure 16

bears against one of the side walls 4 whereby it is guided during its vertical movements. At its upper portion a fire brick section 20 protected by insulating brick 21 stops loss of heat from the flue structure 16, thereby maintaining a uniformly heated firing structure, and preventing contraction and subsequent cracking due to non-uniform temperature conditions.

10 Extending between the refractory structures 16 is a roof 22 comprising a plurality of individual refractory tiles or blocks of the general construction illustrated in Figure 3 of the drawings. From this figure it will be 15 apparent that alternate transverse rows of the refractory blocks are formed with supporting shoulders 23 and suspending projections 24. These suspending projections may be engaged between channels 25 suitably 20 cured to longitudinally extending beams 26 carried at one end by a transverse support 27 bearing at its ends on the walls 3 and 4 forming the outer shell of the furnace, and at its opposite end directly in the end shell. These 25 channels serve in turn to support the alternate rows of blocks. The intermediate rows are formed with ribs or flanges 28 adapted to engage the shoulders 23 on which they are supported. It is thus possible to provide a 30 flat top type arch eliminating the difficulties of usual sprung arch construction, and consequently the troubles inherent in the satisfactory maintenance of such types of roofs.

35 Within the firing chamber the bottom 11 may carry a series of article supports 29 on which the enameled articles rest during the firing operation.

From the foregoing construction it will be 40 apparent that I have provided a muffle type furnace in which the muffles are physically located within the firing chamber so as to increase the radiating surface and consequently the efficiency of the furnace structure. These 45 muffles are in turn effectively insulated to cut down heat losses, and are prevented from discharging their contents into the firing chamber by reason of the refractory structures 16 which are carried thereby in a floating relationship so as to always maintain the desired gas conducting relationship therewith.

To those skilled in the art it will be apparent that the buck stays 30, illustrated more particularly in Figure 1, which may in 50 turn be stayed or tied together in any usual manner, are effective for reinforcing the entire furnace structure. If desired, a light metal casing 31 may be provided intermediate the buck stays and the walls 3 and 5 55 for further insulating and reinforcing the furnace shell.

The provision of the flat roof intermediate the refractory structures and suspended from the shell of the furnace also constitutes an ad- 60 vantageous feature in connection with the

invention and serves to satisfactorily confine the refractory structures 16 during their vertical movements.

While I have herein illustrated and described a preferred embodiment of my invention, it will be understood that the drawings are illustrative only and that changes in the construction, operation and contour of the parts may be made without departing either from the spirit of my invention or the scope of my broader claims.

I claim:

1. In a furnace of the muffle type, a series of walls defining a firing chamber, a flat type roof forming the top of said chamber, a floating flue structure intermediate said roof and walls, and muffles carrying said flue structure.

2. In a furnace of the muffle type, walls defining a firing chamber, a series of muffles within said chamber and spaced from said walls, and a floating flue structure carried by said muffles and into which the muffles of the series open.

3. In a furnace of the muffle type, walls forming a firing chamber, a combustion chamber below said firing chamber, a gas-tight floor intermediate said chambers, muffles within the firing chamber communicating at their lower ends with the combustion chamber, and a floating flue structure carried by said muffles at their upper ends and into which said muffles open.

4. In a furnace of the muffle type, walls forming a firing chamber, a flat type roof forming the top of said chamber, a combustion chamber below said firing chamber, a gas-tight floor intermediate said chambers, muffles within the firing chamber communicating at their lower ends with the combustion chamber, and a floating flue structure carried by said muffles at their upper ends, and into which the muffles open.

5. In a furnace of the muffle type, walls forming a firing chamber, a combustion chamber separate from said firing chamber, a gas-tight partition separating said chambers, muffles within the firing chambers communicating at one end with the combustion chamber, a floating flue structure carried by said muffles at their ends opposite the combustion chamber, said flue structure having openings therein communicating with the adjacent ends of the muffles.

6. In a furnace of the muffle type, walls forming a firing chamber, a flat type roof forming the top of said chamber, a combustion chamber separate from said firing chamber, muffles within the firing chamber communicating at the lower ends with the combustion chamber, and a floating flue structure intermediate said roof and walls carried by said muffles at their upper end, said flue structure having openings therein communicating with the openings in the upper ends of the muffles.

7. In a muffle type furnace, a chamber having opposite side walls, a roof structure interposed between the side walls and spaced therefrom, a flue in the space between the top and side walls and serving to close such space, and a plurality of muffles providing columns for supporting said flue independently of the top and side walls.

8. In a muffle type furnace, a chamber having opposite side walls, a roof structure interposed between the side walls and spaced therefrom, a flue in the space between the top and side walls and serving to close such space, and a plurality of muffles providing columns for supporting said flue independently of the top and side walls, said chamber having a bottom and a combustion chamber below the bottom communicating with said muffles.

9. In a furnace of the muffle type, a bottom combustion chamber, a series of muffles extending vertically and all communicating at one end with said combustion chamber, a flue structure common to a plurality of said muffles and directly supported by the muffles at their upper ends, said flue structure having a plurality of openings into and through which said muffles discharge, and a stack into which said flue structure discharges adjacent the upper portion of the furnace.

30 In testimony whereof I have hereunto set my hand.

HENRY C. JURS.
